poration of Delaware

Filed Feb. 4, 1960, Ser. No. 59,259

Term of patent 14 years

(Cl. D48—16)

FIG. 1.

FIG. 2.

Fig. 2.

Fig. 4.

Fig. 5.

Fig. 6.

Fig. 1 is a perspective view of a lens for lighting fixtures showing my new design;

Fig. 2 is a perspective view thereof as seen from the bottom and opposite end of Fig. 1;

Figs. 3, 4 and 5 are enlarged fragmentary views thereof showing the details of the lens in the rectangular areas 3, 4 and 5 of Fig. 1; and

Fig. 6 is an enlarged fragmentary view thereof showing the details of the lens in the rectangular area 6 of Fig. 2.

The characteristic features of my design for the lens

disclosed reside in the prismatic formation of the lens as best shown in Figs. 3, 4, 5 and 6 on the drawing.

I claim:

The ornamental design for a lens for lighting fixtures, as shown and described.
